US0D1114430S

(12) **United States Design Patent** (10) **Patent No.:** **US D1,114,430 S**
(45) **Date of Patent:** **** Feb. 17, 2026**

(54) **CAR WASHING MACHINE**

(71) Applicant: **Zhejiang Yigoli Intelligent Technology Co., Ltd.**, Hangzhou (CN)

(72) Inventor: **Hengzhi Shi**, Hangzhou (CN)

(73) Assignee: **Zhejiang Yigoli Intelligent Technology Co., Ltd.**, Hangzhou (CN)

(**) Term: **15 Years**

(21) Appl. No.: **29/903,073**

(22) Filed: **Sep. 20, 2023**

(51) LOC (15) Cl. **15-05**

(52) U.S. Cl.

USPC **D32/4**

(57) **CLAIM**

The ornamental design for a car washing machine, as shown and described.

DESCRIPTION

FIG. 1 is a first perspective view of a car washing machine showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the car washing machine that form no part of the claimed design.
